UNITED STATES PATENT OFFICE

2,492,547

AIR COMPRESSOR

Donald E. Willard, Danville, Ill.

Application May 3, 1945, Serial No. 591,752

5 Claims. (Cl. 230—39)

1

My invention relates to air compressors and more particularly to a demountable unit which can be readily attached to the power take-off shaft of a variety of tractors, or generally any source of power.

Compressors of the type contemplated by this invention are customarily used by farmers as a source of compressed air for the tractor tires whose pressure is desirably varied for maximum traction in accordance with the nature and condition of soil over which the tractor operates, and also for spraying, and may also be used by contractors of various kinds, the military service, and industrial concerns.

Cardinal requirements of such compressors are that they be rugged in construction while embodying simplicity of design which is reflected in low manufacturing costs, and, further, that they may be easily disassembled and assembled for purpose of repair and replacement.

It is therefore one object of my invention to provide an air compressor of the character indicated which can be fabricated from simply shaped parts and quickly assembled by unskilled labor.

A further object is to devise a compressor which is equipped with a novel arrangement of valves for controlling the flow of air into and out of the cylinder part thereof.

These and further objects of my invention will be set forth in the following specification, reference being had to the accompanying drawings, and the novel means by which said objects are effectuated, will be definitely pointed out in the claims.

In the drawings:

Fig. 1 is a sectional elevation of my improved compressor.

Fig. 2 is a section along the line 2—2 in Fig. 1.

Fig. 3 is a sectional elevation showing an alternative method of constructing the compressor cylinder.

Fig. 4 is an enlarged, sectional elevation of the lower portion of the compressor, as viewed in Fig. 1.

Fig. 5 is a plan view of the outlet valve housing.

Fig. 6 is a section along the line 6—6 in Fig. 5.

Fig. 7 is a view of the outlet valve housing looking in the direction of the arrow 7 in Fig. 6.

Fig. 8 is a plan view of the outlet valve.

Referring to Fig. 1, the numeral 10 designates a shell bearing that may be made from tubing having an appropriate wall thickness and in which rotates a sleeve journal 11 that is inwardly formed with driving lugs 12 for driving connection with the end of a splined, power take-off shaft (not shown) over which the journal is slipped. Endwise movement of the journal relative to the bearing 10 is prevented by a flange 13 formed on one end of the journal and a ring 14 that is snapped into a groove 15 at the opposite end, the flange 13 and ring 14 abutting op-

2

posite ends of the bearing 10, respectively. If desired, wear rings 15a may be interposed between the ends of the journal and the flange 13 and ring 14, respectively.

5 The flanged end of the journal 11 is provided with a crank pin 16 which is joined by a connecting rod 17 to a piston 18 that is reciprocable in a cylinder 19. The cylinder may be formed by deep drawing a smooth, steel plate to form a cylindrical side wall 20 and an annular, inward flange 21 at the lower end of the cylinder, as viewed in Fig. 1. It is contemplated that the cylinder may be formed from tubing of appropriate gage and inside diameter which is hammered, or rolled, or otherwise deformed at one end to provide the flange 21. A cylinder made in accordance with either of these methods does not require any machining to provide a smooth, working surface for the piston since the original surface of the plate or tube is entirely adequate, considering the nature of the service. The flange 21 rests on a shelf 22 and is fastened thereto by means of a thimble 23 that extends through the flange and shelf and is provided on its upper end with a flange 24 that overlies the cylinder flange 21. This assembly is clamped to the shelf by a nut 25 threaded on the thimble 23 below the shelf. Sealing washers 26—26 may be interposed between the flange 21, and the flange 24 and shelf 22, respectively, to provide an air tight connection.

10 The head of the piston 18 is provided with a plurality of air inlet passages 27 whose lower ends are closed during the compression stroke by a valve 28 carried by a stem 29 that is slidable through the piston head and is encircled above the head by a helical spring 30 whose ends abut the head and a washer 31 on the stem, respectively. The spring 30 yields sufficiently during each suction stroke of the piston to permit the valve 28 to open and air to flow into the compression chamber of the cylinder.

15 During the compression stroke of the piston, the valve 28 closes and the compressed air is forced through a valve mechanism in the thimble. Specifically, the thimble 23 is chambered as at 32 downwardly from the top thereof to receive, as by a forced fit, an inverted cup 33 whose top wall includes an aperture 34 (see Figs. 5 to 8, inclusive) which communicates with the compression chamber of the cylinder. Beneath the aperture 34 is a thin, light and freely movable, valve plate 35 which, in plan view, may possess the hexagonal shape shown in Fig. 8 and which rests 20 on a pair of cross wires 36—36 whose ends are carried by the side wall of the cup 33. During suction strokes of the piston 18, the valve 35 is lifted to close the aperture 34 and is moved to the open position shown in Fig. 1 during compression strokes, the aperture 34 and the marginal opening between the edge of the valve 35 and the side wall of the cup, or either of these

factors, being adjusted to insure a sufficient throttling action on the discharging air to provide an adequate compression of the air. Air passing into the chamber 32 is discharged through a communicating passage 37 in the thimble 23 which may be extended to provide a nipple for connection to an air hose.

The shelf 22 is bent laterally from a plate arm 39 which is apertured as at 40 to snugly receive the bearing 10, the arm extending radially from the bearing. The arm 39 is held against movement axially of the bearing by annular ridges 41-41 projecting outwardly of the bearing closely adjacent the opposite faces of the arm and which may be formed by offsetting the wall of the bearing. In order to insure that the arm 39 will not rotate around the bearing, each face of the arm is provided with a group of circumferentially spaced notches 42, the group in one face being circumferentially displaced from the group in the other face, as shown in Fig. 2, and the adjacent portions of the ridges 41 are forced into and establish an interlocking relation with the notches.

Lubricant fittings 43 of well known type may be mounted in the bearing 10, the crank pin end of the connecting rod 17, and in the wall of the cylinder 19 for connection with any suitable mechanism for force feeding lubricant, the arm 39 being apertured at 44 to provide access to the fitting which is attached to the cylinder wall.

In use, the journal 11 is merely slipped over the end of a power take-off shaft, and the arm 39 is anchored against any tendency to rotate with the journal by fastening chains or cables to a convenient part of the tractor and to ears 45 provided on the arm 39. The bearing surfaces 49 and 50 within the journal 11 are bored concentric with the outer surface of the journal and provide an adequate bearing for spaced portions of the power take-off shaft.

In Fig. 3 is illustrated an alternative cylinder design in which a cylindrical shell 46 forms the side wall of the cylinder and secured to one end thereof is a cup having a cylindrical portion 47 which encircles and closely fits the shell 46 and an annular, inward flange 48 which corresponds in shape and function to the flange 21.

I claim:

1. An air compressor comprising a bearing member, an arm extending generally radially from the member and having a part constituting an extension thereof to provide a laterally disposed shelf, a cylindrical shell having at one end an inward, annular flange seated on the shelf, a thimble extending through the shelf and having a flange engaging the inner surface of the shell flange, nut means threaded on the thimble whereby the shell flange is clamped between the shelf and thimble flange, a piston operable in the shell, and a driving element journaled in the member and adapted for connection to a power shaft, the element having a crank pin connected to the piston.

2. An air compressor comprising a bearing member, an arm extending generally radially from the member and having a laterally disposed shelf, a cylindrical shell having at one end an inward, annular flange seated on the shelf, a thimble extending through the shelf and having a flange engaging the inner surface of the shell flange, nut means threaded on the thimble whereby the shell flange is clamped between the shelf and thimble flange, a piston operable in the shell having a valve controlled passage

through the head thereof which opens during suction strokes of the piston and closes during compression strokes, the thimble having an air passage providing an exit for the compressed air, a valve means in the thimble passage arranged to provide only an exhaust flow of air, and a driving element journaled in the member and adapted for connection to a power shaft, the element having an eccentric connection with the piston.

3. An air compressor comprising a bearing member, an arm extending generally radially from the member and having a laterally disposed shelf, a cylindrical shell having at one end an inward, annular flange seated on the shelf, a thimble extending through the shelf and having a flange engaging the inner surface of the shell flange, nut means threaded on the thimble whereby the shell flange is clamped between the shelf and the thimble flange, a piston operable in the shell having a valve controlled passage through the head thereof which is open during suction strokes of the piston and is closed during compression strokes, the thimble having an air passage providing an exit for the compressed air, a thin valve having a weight such that it is moved to close the thimble passage during suction strokes of the piston and opens during compression strokes, and a driving element journaled in the member and adapted for connection to a power shaft, the element having an eccentric connection with the piston.

4. An air compressor comprising a sleeve bearing, a radial arm through which the bearing extends in tight fitting engagement therewith, the sleeve bearing having offset, peripheral formations contacting opposite sides of the arm to prevent movements thereof axially of the bearing, a shelf projecting laterally from the arm, a cylinder having one end seated on the shelf, a piston operable in the cylinder, and a driving element journaled in the bearing and adapted for connection to a power shaft, the element having an eccentric connection with the piston.

5. An air compressor comprising a sleeve bearing, a radial arm through which the bearing extends in tight fitting engagement therewith, the bearing having offset, peripheral formations fitting into notches provided on opposite sides of the arm for preventing relative rotation and movements of the arm axially of the bearing, a shelf projecting laterally from the arm, a cylinder having one end seated on the shelf, a piston operable in the cylinder, and a driving element journaled in the bearing and adapted for connection to a power shaft, the element having an eccentric connection with the piston.
